GRAIN SPOUT

Leo A. Emanuelson, 6201 4th Ave. S.,
Minneapolis 23, Minn.

Filed Apr. 13, 1959, Ser. No. 805,832
9 Claims. (Cl. 193—25)

The herein disclosed invention relates to flexible grain spouts and has for an object to provide a flexible grain spout consisting of telescoping sections connected together by chains and in which the wear may be distributed throughout the entire circumferential area of the sections.

Another object of the invention resides in providing a grain spout in which the sections may be easily and quickly rotated relative to one another and relative to the supporting structure to prevent undue wear at certain portions of the sections.

A still further object of the invention resides in constructing each section with a tubular body tapered in form and in providing the upper and larger ends of the body with an outwardly extending rim having an outwardly extending flange and a downwardly extending skirt forming a downwardly facing annular recess and in providing a number of pairs of oppositely disposed notches in the lower marginal portion of the skirt open from beneath.

Another object of the invention resides in providing a ring adapted to encircle the body and to enter said recess from beneath and to further provide pins extending outwardly from said ring and adapted to be received in said notches, said rings being connected together by chains adapted to support the sections for articulation, said sections being circumferentially adjustable relative to the rings to bring the pins into engagement with different notches in the skirts of the rims.

Other objects of the invention reside in the novel combination and arrangement of parts and in the details of construction hereinafter illustrated and/or described.

In the drawings:

FIG. 1 is an elevational view of a flexible grain spout illustrating an embodiment of the invention.

FIG. 2 is a plan sectional view taken on line 2—2 of FIG. 1.

FIG. 3 is a perspective view of one of the supporting rings of the invention.

FIG. 4 is a longitudinal sectional detail view taken on line 4—4 of FIG. 2 and drawn to a greater scale.

The invention consists of a number of sections 10, 11, 12, 13, etc., usually about twelve sections connected together. Each of the sections is identical in construction and only the section 10 which is shown in detail in FIGS. 2 and 4 will be described. This section consists of a tubular body 14 constructed of sheet metal and which is tapered, being of greatest diameter at its upper end 15 and of least diameter at its lower end 16. The upper end of the body portion 14 is formed with a rim 20 having an outwardly extending flange 16 and a skirt 17 depending therefrom and spaced from the body proper. This construction provides an annular space 18 between said rim and body 14 closed at the upper end through the flange 16. The skirt 17 is formed with an even number divisible by four of equally spaced notches 19 along its lower exposed edge 29.

Operating in conjunction with the body 14 is an annular ring 21 shown in detail in FIG. 3. This ring is of such dimension as to freely fit within the space 18 of the body 14 as shown in FIG. 4. The said ring has four pins 22 projecting outwardly therefrom and which are adapted to be disposed in any of the notches 19.

For connecting the sections together, a number of chains 23 are provided which have links of sufficient size to receive the pins 22. These links fit over the pins and cotter keys 24 extending through the outer ends of said

2

pins hold the links attached to the same. By means of this construction, the various sections may articulate to cause the spout to flex and move to various positions to deliver the grain to the desired locality.

5 The upper section 12 of the spout is attached to a connecting fitting 25 which forms part of the regular equipment of the elevator in which the spout is used. This fitting has at its lower end a neck 26 which extends into the spout 12. The same also has issuing outwardly from it lugs 27 and to which the upper ends of the chains 23 are attached.

10 The device is used in the customary manner. However, at frequent intervals the tubular bodies 14 of the sections are raised until the notches 29 clear the pins 22. The bodies can then be rotated so that the pins will be received in other notches. Thus the wear on the sections can be distributed and the life of the spout greatly lengthened.

15 The advantages of the invention are manifest. The life of a grain spout constructed in accordance with the invention is greatly lengthened. The parts can be readily assembled and all of the corresponding parts being identical in construction, spare parts can be maintained on hand and the spout continuously kept in operating order. The parts are easily assembled and the adjustment to reduce wear easily and quickly made.

20 Changes in the specific form of the invention, as herein described, may be made within the scope of what is claimed without departing from the spirit of the invention.

25 Having described the invention, what is claimed as new and desired to be protected by Letters Patent is:

1. A flexible grain spout comprising a number of sections each having a tapered telescoping body formed with a rim at its upper larger end, an annular supporting structure encircling said body, said body being circumferentially movable relative thereto, said body having circumferentially arranged diametrically disposed pairs of contact members and cooperating pairs of contact members on said rim interchangeably engageable with the contact members of said supporting structure, means on said contact members restraining circumferential movement between said supporting structures and bodies when said contact members are engaged, and tethering means connecting said supporting structures together.

2. A flexible grain spout comprising a number of sections each having a tapered telescoping body with the larger end uppermost, a supporting structure encircling said body at its upper end and circumferentially movable relative thereto, said supporting structure having circumferentially arranged spaced upwardly facing contact members, said body having at its upper end downwardly facing cooperating contact members interchangeably engageable with the contact members on said supporting structure, said cooperating contact members having longitudinally extending contacting surfaces, which when said contact members are engaged restrain relative circumferential movement between said supporting structures and bodies, and tethering means connecting said supporting structures together.

3. A flexible grain spout comprising a number of sections each having a tapered telescoping body with the larger end uppermost, a rim issuing outwardly from the upper end of said body, a ring encircling said body portion at the locality of said rim and movable circumferentially relative thereto, said ring having circumferentially arranged spaced upwardly facing contact members, said rim having downwardly facing cooperating spaced contact members interchangeably engageable with the contact members of said ring, means on said contact members restraining circumferential movement between said rings and said bodies when said contact members are engaged and tethering means connecting said rings together.

4. A flexible grain spout comprising a number of sections each having a tapered telescoping body with the larger end uppermost, a supporting structure encircling said body at its upper end and circumferentially movable relative thereto, said supporting structure having a circumferential part, and said body having a juxtaposed circumferential part, one of said parts having a number of circumferentially arranged fulcrums, and the other of said parts having a number of sockets adapted to receive said fulcrums and interchangeably engageable therewith, said fulcrums and sockets providing, when in engagement, surfaces restraining circumferential relative movement between said supporting structures and bodies, and tethering means connecting said supporting structures together.

5. A flexible grain spout comprising a number of sections each having a tapered telescoping body with the larger end uppermost, a rim issuing outwardly from the upper end of said body, a ring encircling said body at the locality of said rim and movable circumferentially relative thereto, said ring having circumferentially arranged spaced upwardly facing pins issuing radially outwardly therefrom, said rim having downwardly facing open sockets interchangeably laterally engageable with said pins, and tethering means connecting said rings together.

6. A flexible grain spout comprising a number of sections each having a tapered telescoping body with the larger end uppermost, a rim issuing outwardly from the upper end of said body, a ring encircling said body at the locality of said rim and movable circumferentially relative thereto, said ring having circumferentially arranged spaced pins issuing radially outwardly therefrom, said rim having sockets facing said pins and interchangeably laterally engageable therewith, and tethering means connecting said rings together.

7. A flexible grain spout comprising a number of sections each having a tapered telescoping body with the larger end uppermost, a rim at the upper end of said body portion and having an outwardly extending flange and a depending skirt issuing therefrom and forming a downwardly facing annular recess encircling said body, upon

35
40

the exterior thereof and opening downwardly, a ring encircling said body and received in said recess, said ring having radially extending pins issuing outwardly therefrom and projecting beyond said skirt, downwardly facing open sockets formed on the lower edge of said skirt and interchangeably receiving said pins, and tethering means connecting said rings together.

8. A flexible grain spout comprising a number of sections each having a tapered telescoping body with the larger end uppermost, a rim at the upper end of said body and having an outwardly extending flange and a depending skirt issuing therefrom and forming a downwardly facing annular recess encircling said body, upon the exterior thereof and opening downwardly, a ring encircling said body portion and received in said recess, said ring having radially extending pins issuing outwardly therefrom and projecting beyond said skirt, downwardly facing open sockets formed on the lower edge of said skirt and interchangeably receiving said pins, and tethers connected to said pins.

9. A flexible grain spout comprising a number of sections each having a tubular body telescoping with the adjoining body, a rim at the upper end of said body and having an outwardly extending flange and a depending skirt issuing downwardly therefrom said skirt having downwardly facing open sockets formed on the lower edge thereof, a supporting structure disposed below said flange and having contact members interchangeably received in the sockets in said skirt and when received therein restraining circumferential relative movement between said supporting structures and said bodies.
